UNITED STATES PATENT OFFICE.

HOMER J. CRAGUN, OF LOGANSPORT, INDIANA.

FLYING-MACHINE.

No. 883,090.

Specification of Letters Patent. Patented March 24, 1908.

Application filed March 6, 1907. Serial No. 380,810.

To all whom it may concern:

Be it known that I, HOMER J. CRAGUN, a citizen of the United States, residing at Logansport, in the county of Cass and State of Indiana, have invented certain new and useful Improvements in Flying-Machines, of which the following is a specification.

This invention relates to flying machines and more particularly to those of the self sustaining type which do not employ gas fields, and has for its object to provide a machine of this kind provided with means adapted for use at times as a lifting agent and at times as a propelling agent.

15 Another object is to provide a flying machine including novel features of structure and arrangement of parts tending to produce a machine possessing great strength with a minimum weight.

20 Other objects and advantages will be apparent from the following description and it will be understood that changes in the specific structure shown and described may be made without departing from the spirit of 25 the invention.

In the drawings forming a portion of this specification and in which like numerals of reference indicate similar parts in the several views: Figure 1 is a side elevation of the 30 complete machine, Fig. 2 is a top plan, of one of the fan wheels, Fig. 3 is a view similar to Fig. 1 showing the fan wheels tilted into propelling position, Fig. 4 is a sectional view of one of the fan wheels, Fig. 5 is an end view. 35 Fig. 6 is a detail section of the mounting of one of the shafts.

Referring now to the drawings, the present invention comprises a frame consisting of two bottom side-bars 6 & 7 respectively, 40 which are mutually connected at their ends and which diverge toward their centers as shown. These side-bars are bent downwardly at their centers, as indicated at 8 and extending upwardly from the centers of the 45 side-bars there are convergent rods 9.

The side-bars 6 and 7 extend longitudinally of the machine, as shown, and these bars have secured thereto at their ends bearing blocks 10 in which are journaled the end 50 portions of a longitudinally extending shaft 11. These bearing blocks 10 are formed by the lower end portions of a pair of uprights 12 and a pair of crossed brace rods 13 are secured at their lower ends to the bearing 55 blocks 10 and at their upper ends to the uprights 12 adjacent to the upper ends thereof;

these brace rods thus extending longitudinally of the machine.

As shown, the convergent rods 9 are secured at their upper ends to the brace rods 60 13 at their crossing point, so that there is formed a strong though light structure, and carried by the brace rods at their point of connection with the rods 9, there is a seat 9'. Outwardly extending vertically spaced brackets 65 14 are carried by the uprights 12, and journaled in each pair of these brackets, there is a vertical shaft 15, connected at its lower end with the adjacent end of the power shaft 11 by means of bevel gears 16.

A yoke 17 is carried by the upper end of each of the uprights 12, the arms 17' of which extend outwardly over the adjacent shaft 15, and in the arms of each yoke there are mounted the trunnions 18 of an upwardly extending member 21, which is thus movable longitudinally of the machine, and revolvably mounted in this member there is an upwardly extending wheel shaft 22, carrying at its lower portion a horizontally extending bevel gear 23, which meshes with the upper portion of a bevel gear 19, mounted upon one of the trunnions 18 outwardly of the yoke and meshing at its lower portion with a similar horizontal gear 20 carried by the upper end of the adjacent shaft 15, for rotation thereby. The two ends of the machine are thus constructed in the same manner, and upon the upper end of each wheel shaft 22, there is mounted a propeller 24, of the fan wheel type, consisting 90 of a hub 25 and radial blades 26 which are transversely curved, and which overlap each other circumferentially of the wheel, while being in mutual spaced relation, and these blades slant downwardly toward their outer 95 ends, so that the wheels are given an umbrella shape. The blades are supported by ribs 27, secured thereto and to the wheel shafts 22, and from the just described mechanism, it will be seen that the fan wheels will 100 be revolved with the shaft 11.

By reason of the fact that the members 21 are shiftable pivotally upon the pivot pins 18, the fan wheels 24 may be shifted from the horizontal toward the vertical. To accomplish this movement, angle levers 29 are pivoted to the yokes 17 at the inner portions thereof, and are connected at the ends of their upwardly extending arms 30 with the members 21, above the pivot points of the latter, by means of links 30'. Rods 31 connect the horizontal arms 32 of the angle

2
levers with similar levers 33 mounted at the lower portions of the uprights, and horizontal rods 34 are connected to these levers 33 and with a hand lever 35, located within reach of the seat 9', and pivoted to a portion of the frame, this hand lever being provided with stop mechanism to hold it at different points of its movement. It will thus be understood that the two fan wheels may be shifted simultaneously from the horizontal 10 to a diagonal position, and vice versa.

A motor 36 is mounted upon the side-bars 6 and 7, and between the rods 9, and is connected with the shaft 11 for rotation thereof, 15 as shown at 37. A steering vane 38 is mounted at the rearward end of the machine and is operatively connected with a steering post 39.

In operation, when it is desired to ascend 20 into the air, the motor is started, and the fan wheels having been brought to horizontal position, their action will cause the machine to rise, when, if it be desired to move horizontally, the wheels are shifted into a diagonal position which will give the machine an upward and diagonal motion.

It will be obvious that I may employ with the lifting and propelling mechanism just described, any of the usual aeroplane structures of common use if I so desire.

As shown, the shifting mechanism is such that the fan wheels are moved in the same direction when the hand lever is operated.

What is claimed is:

35 In the flying machine, the combination with a frame consisting of two longitudinally extending bottom side bars which are mutually connected at their ends and which diverge toward their centers, the bottom side 40 bars being bent downwardly at their centers,

convergent rods secured to the side bars and at the center thereof and extending upwardly, a pair of uprights secured at each end of the side bars, crossed brace rods connecting the uprights, the lower ends of the 45 uprights having bearing blocks, a longitudinally extending drive shaft journaled in the bearing blocks, the upper ends of the convergent rods being secured to the crossed brace rods, a motor carried by the frame and supported upon the side bars, connections between the motor and the drive shaft, vertical shafts carried by the uprights, and connected with the drive shaft, yokes carried by the uprights, members pivotally mounted in the 50 yokes, shafts revolubly connected with the members, gears pivotally mounted upon the yokes concentrically with the pivot points of the members, gears carried by the vertical shaft and by the second named shafts 55 respectively and meshing with the first named gears, angle levers pivoted to the yokes, connections between the angle levers and the members between the yokes, angle levers pivoted to the uprights and beneath the first 60 named angle levers, rods connecting the horizontal arms of the angle levers, a rod connecting the vertical arms of the last named angle levers, a lever pivoted to the convergent rods and to the rod connecting the vertical arms of the last named angle levers and 65 arranged to shift the rod to tilt the members between the yokes, and a steering apparatus arranged at the rear of the frame.

In testimony whereof I affix my signature 70 in presence of two witnesses.

HOMER J. CRAGUN
